WASH MACHINE

Bronislaw Goldman, Canton, Ohio

Application March 25, 1941, Serial No. 385,125

3 Claims. (Cl. 68—27)

My improvements refer to a wash machine of the type which is commonly employed for household uses and in which the washing process is performed by setting the liquid in which the washing is performed into motion by means of a motor-driven agitator. The purpose of my invention is to provide an agitator of a very simple construction and yet capable of high degree of efficiency.

Another and very important purpose of my invention is to provide means within my wash machine for the purpose of removing moisture from the objects which had been washed therein. What my invention contemplates is a machine of the type which not only is capable of performing the washing operation but which also can be used for the purpose of drying the objects which had been washed and this without the use of any complicated devices or any extra containers. As a matter of fact, as will be later shown, the machine of my invention can perform both functions at the same time. It can be applied to perform the washing operation, while at the same time, by means of the same shaft which drives the agitator for washing purposes and within the confines of the receptacle in which the washing is done, another member of the machine may be utilized for the purpose of drying out the objects which had been washed before.

Another purpose of my invention is to effect an economy of the washing liquid by combining the washing and the drying means of my machine in the same receptacle so that the liquid driven out by the drying means may be utilized for washing purposes.

Another purpose of my invention is to secure the liquid available from the drying operation for washing purposes without the use of any pumps or other special mechanism.

Having thus indicated in general the purposes for which my improvements have been devised, I shall now describe them with reference to the accompanying drawing, in which:

Fig. 1 shows a vertical sectional view of my machine.

Fig. 2 shows a horizontal sectional view of my machine taken on line 2—2.

Fig. 3 shows a perspective view of the drying element of my machine.

Fig. 4 shows a fragmentary sectional view of another form of my machine.

Similar numerals refer to similar parts throughout the several views.

The wash machine of my invention comprises a receptacle 10, closed at the bottom and open

at the top, but provided with a removable cover 11 in which 12 indicates a handle. The receptacle may be in the form of a drum, although the shape is not critical, and a rectangular or some other form may as well be used. The drum is mounted on a platform 13, supported on a stand 14. A motor 15 is attached to the underside of the platform 13 by means of bolts 16. The shaft 17 of the motor 15 extends through the center of the platform 13 into the interior of the drum 10, where it is axially disposed with reference thereto. The shaft, in its upper part, within the drum, may be either flattened on one side or square in cross-section. A packing 18 is provided around the shaft right under the bottom of drum 10 where said shaft enters said drum. A cylindrical drum 19 having a socket 20 is seated on shaft 17. The drum is closed at the bottom to prevent access of the clothes, and the drum 19 because of its rotating movement must be in sliding contact with the receptacle to prevent the clothes from wrapping around shaft 17.

The top of the agitator drum 19 is provided with a radial flange 22 for supporting a perforated drum 24. The drum is secured to the agitator 19 by means of bolts 23a, fitted into openings 23 of flange 22 and openings in the bottom 26 of drum 24. The drum 24 is of a diameter somewhat larger than that of the agitator. It is open at the top and provided with a plurality of perforations 25 in its wall.

A number of fin-like baffles 27 project from the interior wall of my receptacle 10, to serve a purpose which will be later described. The upper edge of the fins extends to a point somewhat above the level of the bottom of drum 24.

The washer shown in Fig. 4 is substantially the same as that shown in Fig. 2. In this case the receptacle is indicated by numeral 28; the perforated dryer by numeral 29; the agitator by numeral 30. It will be seen that the agitator is also provided with perforations 31. These perforations serve to enhance the efficiency of the agitator in setting the liquid within the receptacle into a rotary motion. The proportion between the size of the receptacle and the size of the agitator and the dryer within is somewhat different than that shown in Fig. 1, but this is obviously optional, if the diameter of the dryer provides sufficient room for removal of the clothes through the space between the dryer and the receptacle wall. Likewise, the diameter of the agitator drum is optional if its periphery is suf-

ficiently large to prevent tangling of the clothes in the receptacle.

As I have indicated in the beginning, the purpose of my machine is not only to perform washing, but also to serve as a centrifugal drier. Ordinarily when washing is to be done, the receptacle is to be filled with liquid which should reach to a point below the level of the top of the agitator. This naturally is not a critical requirement, although preferable for best results. Then the motor is started and a rotary motion is imparted to the agitator 19. Even if the wall should be entirely smooth, although it need not be, the liquid within the receptacle would be set into a rotary motion by reason of adhesion of the liquid to the surface of said agitator 19. This is true particularly if the motor is made to rotate rapidly. Since a degree of turbulence and commotion of this liquid is desirable, this is secured by means of baffles 21. When washing is being thus performed, the drum 24 rotates together with the agitator and the only service that it may perform is that the liquid thrown against the baffles and rebounding from the interior wall of receptacle 10 against said drum is stopped by the external surface of the drum and made to drop back into the receptacle. But while the washing is being performed in the lower part of the receptacle 10, drum 24, which is rapidly rotated by the agitator, may be utilized as a conventional centrifugal drier. The rotary motion of the drier causes liquid absorbed in washing by the objects placed in the drier to be thrown out through perforations 25. Said liquid would, by gravity, find its way to the lower part of the receptacle where it can contribute to the quantity of the liquid contained therein.

Although the lower part of the agitator is capable of performing its function separately and independently of the upper part, and although the upper part, that is the drum, may be used separately without reference to the function of the agitator, it will be seen that both said elements, that is, the agitator and the drum, act in combination, as the shaft which operates the agitator also operates the drum, thus eliminating the necessity of a separate container for the drier, also because the liquid which is thrown out by the drier 24 flows back into the lower part of the receptacle where it performs a useful function in conjunction with the agitator.

To sum up, the improvement shown by me eliminates the necessity of a separate drier and

makes it possible to carry on simultaneously what otherwise would be successive stages of washing and drying suitable objects.

Reiterating my remarks that the machine is capable of some changes without departing from the spirit of my invention, I wish to present the following claims:

- 5 1. In a washing machine, a tub for clothing and washing solution having radial projections on the inner wall thereof, a rotor mounted centrally and extending substantially the full vertical height of the tub having a cylindrical bottom portion of substantial diameter for subjecting the washing liquid and clothes to circular movement against the resistance of the radial projections of the receptacle, and said rotor having a perforated upper portion constituting a centrifugal drier receptacle of a diameter sufficiently less than the wall of the tub to allow for the removal of the clothes through the annular space therebetween, a cover for said tub, and drive means for the rotor.
- 10 2. In a washing machine, a tub for clothing and washing solution, a rotor mounted centrally and extending substantially the full vertical height of the tub having a cylindrical bottom portion of substantial diameter for subjecting the washing liquid and clothes to circular movement, and said rotor having a perforated upper portion constituting a centrifugal drier receptacle of a diameter sufficiently less than the wall of the tub to allow for the removal of the clothes through the annular space therebetween, a cover for said tub, and drive means for the rotor.
- 15 3. In a washing machine, a tub for clothing and washing solution, a cover therefor, a rotor mounted centrally and extending substantially the full vertical height of the tub having a cylindrical bottom portion of substantial diameter and of a length corresponding to the height to which the tub will be filled with clothing and solution, said portion being in such proximity to the base of the tub that no clothing can pass between the base of the rotor and the tub, said rotor being provided with a perforated receptacle of cylindrical form extending above the water level of the tub, which is of a diameter to provide an annular space between the receptacle and the tub of a sufficient width to permit the free handling of the clothing in removing the same from the tub to the receptacle, and drive mechanism for said rotor.
